Patented Apr. 2, 1918.

UNITED STATES PATENT OFFICE.

DONOVAN FOSTER, OF MOSCOW, IDAHO.

HEADLIGHT-LENS.

1,261,375.

Specification of Letters Patent. Patented Apr. 2, 1918.

Application filed September 11, 1917. Serial No. 190,760.

To all whom it may concern:

Be it known that I, DONOVAN FOSTER, a citizen of the United States, residing at Moscow, in the county of Latah and State 5 of Idaho, have invented certain new and useful Improvements in Headlight-Lenses, of which the following is a specification.

The object of this invention is the perfecting of headlight lenses whereby the light 10 rays are directed to effectually illuminate the ground in advance of the vehicle and prevent the direct rays from the light being seen by a person facing the lamp.

The invention consists in the novel construction, adaptation and arrangement of 15 parts in a lens as will be hereinafter described and claimed.

In the accompanying drawings, Figure 1 is a vertical sectional view of a headlight 20 reflector with a lens embodying my improvements applied thereto. Fig. 2 is a horizontal sectional view of the same. Fig. 3 is a detail horizontal sectional view of the improved lens to illustrate the regulation 25 thereby of light rays from a reflector such as represented in the preceding views. Fig. 4 is a front elevational view of the lens shown in Figs. 1 and 2.

Referring to the drawings, the reference 30 numeral 5 designates a parabolic reflector such as usually employed in headlights and 6 represents a lens embodying the various features of the present invention.

The front of the lens is formed with a 35 plurality of superposed prisms A, B, C, etc., having front faces 7¹, 7², etc., which incline forwardly from the upper edges of each to the bottoms 8¹, 8², etc., of the respective prisms, said bottoms being inclined to be 40 parallel, or nearly so, with the reflected rays as bent downwardly by the respective prisms. In the front face of the prism B, which is located directly in front of light, indicated by F (Figs. 1 and 2), is provided 45 a recess of a substantially triangular shape in front elevation (Fig. 4) and having two triangularly shaped plane surfaces 9 which are disposed in angular relations with respect to each other and to a vertical line 10 located in a plane, indicated by broken lines A¹, Fig. 2, passing through the light or inner focus F.

By thus arranging the surfaces 9 the direct rays from the light are bent outwardly 55 as represented by a a in Fig. 2 to render the

light indiscernible to a person in front of the lamp. The recess surfaces 9 are furthermore arranged to slope somewhat forwardly from their upper edges 11 toward the bottom edges 12 thereby directing the 60 light rays downwardly similarly to the aforesaid prisms.

The lens face opposite to that provided with prisms is corrugated by the provision of vertically disposed ridges and concavities, 65 formed and arranged tangentially to furnish a sinusoidal surface comprising alternating convex and concave portions 13 and 14, respectively. The rays from the parabolic reflector are directed therefrom substantially rectangularly to the lens as indicated by darts b, b¹ in Fig. 3, those passing through the convex portions 13 being caused to converge, as at c, to focal lines whence the rays diverge as indicated by d. 75

The reflected rays passing through the concave portions 14 are thereby caused to diverge, as at e, from axial lines f and be diffused among the rays d in advance of a plane, as y—y for example, to produce an 80 illuminated field with an absence of "spots" or unlighted areas.

The forming of the lens with a face having a curve-of-sines surface causes the light rays to be not only more evenly distributed 85 but also spreads them horizontally without diminishing their illuminating value.

What I claim, is—

1. A substantially circular plate headlight lens having a prismatic front face 90 formed to refract downwardly all rays passing through the lens, and a plurality of vertical connected plus and minus cylindrical lenses forming a uniform sinusoidal rear face for said lens, said lenses each being 95 formed to include not more than substantially one-third of a complete cylinder to thereby effect intersection and diffusion of all rays emitted from the lens without reflection thereof. 100

2. A substantially circular plate headlight lens having a plurality of horizontal transverse prisms on its front face formed to refract downwardly all rays passing through the lens, and a plurality of vertical connected alternating plus and minus cylindrical lenses forming a uniform sinusoidal rear face for said lens, said lenses each being formed to include not more than substantially one third of a complete cylinder 105 110

to thereby effect intersection and diffusion of all rays emitted from the lens without reflection thereof.

3. A substantially circular plate headed light lens having a plurality of horizontal transverse prisms on its front face formed to refract downwardly all rays passing through the lens, a plurality of vertical connected alternating plus and minus cylindrical lenses forming a uniform sinusoidal rear face for said lens, said lenses each being formed to include not more than substantially one third of a complete cylinder

to thereby effect intersection and diffusion of all rays emitted from the lens without reflection thereof, and a recess provided centrally in said front face adapted to refract light, passing through the lens directly from a light source, laterally without diffusion.

Signed at Seattle, Washington, this 5th day of September, 1917.

DONOVAN FOSTER.
